UNITED STATES PATENT OFFICE.

JAMES H. EASTMAN, OF DETROIT, MICHIGAN.

ELECTROTHERAPEUTIC APPARATUS.

1,317,278.

Specification of Letters Patent. Patented Sept. 30, 1919.

Application filed May 5, 1919. Serial No. 294,906.

To all whom it may concern:

Be it known that I, JAMES H. EASTMAN, a citizen of the United States, residing at Detroit, in the county of Wayne and State 5 of Michigan, have invented certain new and useful Improvements in Electrotherapeutic Apparatus, of which the following is a specification.

This invention relates to electrotherapeutic apparatus or what is quite commonly called a "violet ray" high-frequency generator. It has for its object an electrode holder and handle so designed, and the apparatus so designed, that the latter may be 10 entirely contained in the former, resulting in a very convenient device that can be made at minimum cost. Heretofore it has been customary to have a handle that contains the high-frequency coil or resonator, and 15 the rest of the apparatus has been usually placed in a portable box.

It is the object of the present invention to so arrange the parts without curtailing their size that they may all be contained within 20 a single handle and the handle itself in no way impaired but rather improved from the standpoint of manipulation and portability.

In the drawings, 30 Figure 1 is a cross section through my improved machine.

Fig. 2 is a longitudinal section of the casting section that forms the electrode-holding tube.

Fig. 3 is a cross section through both sections on the line 3—3 of Fig. 2.

Fig. 4 is a diagrammatic view of the apparatus.

Fig. 5 is a perspective of the assembled 40 casing.

Fig. 6 is a side elevation of the section forming the auxiliary tube.

Fig. 7 is an end elevation of the same.

a designates the cable that in the usual 45 machine now on the market leads from a box containing the condenser, magnet coil, and the vibrator to the handle. Here the cable contains wires which can lead directly to a plug (not shown) that may be screwed 50 into any electric light socket. The casing is made up of two sections forming in the aggregate two tubes connected by a pair of joining tubes *b*, *b*. One tube is partially closed at one end. This end has a central

bore carrying the electrode socket *d* which is 55 in the form of a split tube adapted to grasp the glass vacuum electrode *f*.

By comparing Figs. 5 and 6, an idea of how the casing is split can be had. There 60 are two tubes formed, the tube *g*, which we will call the electrode-holding tube, and the tube *h*, which we will call the auxiliary tube. Fig. 2 shows the section which forms one-half of the auxiliary tube and one-half of 65 each of the joining tubes *b* and the whole of the electrode-holding tube. This is the lower section shown in Fig. 5, while the upper section shown in Fig. 5 and shown alone in Figs. 6 and 7 comprises one-half of 70 the auxiliary tube, one-half of the joining tubes *b* and the entire cap *j*. These sections may be joined by screws *i* that pass through the screw holes *k*. It will readily be understood 75 how this opens up the entire interior for assembling the apparatus itself and having access thereto.

This apparatus comprises a magnet coil *l* provided with an armature carried upon a 80 spring arm *m*, which forms a vibrator to make and break the current for the purpose of giving a pulsating current of high voltage that may be transformed into an induced current of much higher voltage and of high frequency. This is accomplished by 85 the condenser *n* and the induction coil *o*, which are bridged across the interrupter gap and are in series with each other. The condenser and induction coil are contained in the electrode-holding tube while the magnet coil, vibrator and vibrator terminals are contained in the auxiliary tube with a portion 90 of the vibrator spring protruding into the upper joining tube *b*. It is advantageous to use part of the joining tube for this purpose as it gives the spring of the vibrator greater length than would be possible in the ordinary tube.

p is a screw for regulating the limit of 95 the armature swing and pressure between 100 interrupter contacts.

It will be obvious that the auxiliary tube forms a very convenient member to grasp with the hands. The fingers can encircle 105 this and be passed through the opening between the two tubes. The joining tubes *b*, *b* also help in aiding the grip as they prevent the hand slipping either up or down as the distance between the two joining tubes *b*, *b*

is just about the width of the ordinary hand. Or the casing may just as well be grasped by the electrode-holding tube.

This makes an instrument which can be made with tubes of fairly small diameter and of very much less length than would be possible if all the apparatus were contained in a single tube; in fact, the entire instrument can be made within such a compass as to be capable of being carried in one's pocket. It makes, therefore, a machine which is much handier from the standpoint of portability than the ordinary box and electrode holder that has found the most general use heretofore. It also can be made much cheaper as it requires no box to house the parts that cannot be carried in the ordinary handle.

"Tube" is used in the claims to mean a hollow pipe-like construction whether of circular or non-circular cross-section. "Interrupter" is used in the claims to mean broadly any apparatus for interrupting the current to secure a pulsating current. In the apparatus shown the interrupter specifically includes the magnet coil, the vibrator arm and armature and the two vibrator terminals.

What I claim is:

- 30 1. A high-frequency electrotherapeutic instrument, having in combination, a casing made up of two tubes in substantial parallelism but spaced apart by one or more joining tubes forming a communication from one of the first-mentioned tubes to the other, an electrode socket supported in one of the first two mentioned tubes, and apparatus located in said first two-mentioned tubes and wholly in the casing for transforming an electric current into a high-frequency and high voltage current and delivering the same to the electrode socket.
- 40 2. A high-frequency electrotherapeutic instrument, having in combination, a casing comprising an electrode-holding tube and an auxiliary tube connected by one or more joining tubes, the latter entering the first mentioned tube at an angle, a magnet coil and vibrator terminal contained in the auxiliary tube, a vibrator contained partially within a joining tube longitudinally thereof and partially and transversely within the tube containing the magnet coil with which it functions, a condenser and induction coil located in the electrode-holding tube and electrically connected with

each other and the vibrator and vibrator terminal, and an electrode socket in the electrode-holder tube and in electrical connection with the induction coil.

60

3. A high-frequency electrotherapeutic instrument, having in combination, a casing comprising a pair of substantially parallel tubes spaced apart, a pair of joining tubes connecting the first two mentioned tubes at their two ends, an electrode socket supported in one of the ends of the first-mentioned two tubes, and a condenser, induction coil, and interrupter located in the first two-mentioned tubes and electrically connected with each other and with the electrode socket.

70

4. In high-frequency electrotherapeutic apparatus, a casing comprising a shell divided into sections, one section forming the entire electrode-holding tube, half the auxiliary tube and a portion of the inter-connecting members while the other section forms half the auxiliary tube and a portion of the interconnecting members, and a cap for the electrode-holding tube.

75

5. In high-frequency electrotherapeutic apparatus, a casing comprising a shell formed in sections to form an electrode-holding tube, and an auxiliary tube, of which one section forms part of the auxiliary tube and parts of interconnecting tubes between the two longer tubes, and a cap on the electrode-holding tube, while the other section forms the remaining parts of the auxiliary tube and the interconnecting tubes, and a cap for the electrode-holding tube.

80

6. A high-frequency electrotherapeutic instrument, having in combination, a casing comprising a pair of substantially parallel tubes spaced apart, one or more joining tubes connecting the first two mentioned tubes together, an electrode socket contained in one of the first two mentioned tubes, a condenser and induction coil contained in one of the first two mentioned tubes, a magnet and vibrator terminal contained in the other of the first two mentioned tubes, a vibrator arm fastened in the joining tube and having its free end extending between the magnet and the vibrator terminal, and electrical connections connecting the magnet, vibrator terminal, vibrator arm, condenser, induction coil, and socket.

85

In testimony whereof I affix my signature.
JAMES H. EASTMAN.
